UNITED STATES PATENT OFFICE.

WILLIAM H. LEE, OF SYRACUSE, NEW YORK, ASSIGNOR TO SYRACUSE CHILLED PLOW COMPANY, OF SYRACUSE, NEW YORK, A CORPORATION OF NEW YORK.

MEANS FOR RAISING AND LOWERING THE EARTH-TURNING ELEMENT OF WHEELED PLOWS.

1,072,863.

Specification of Letters Patent. Patented Sept. 9, 1913.

Application filed September 29, 1910. Serial No. 584,387.

To all whom it may concern:

Be it known that I, WILLIAM H. LEE, of Syracuse, in the county of Onondaga and State of New York, have invented a certain 5 new and useful Means for Raising and Lowering the Earth-Turning Elements of Wheeled Plows, of which the following is a specification.

My invention relates to wheeled plows, 10 and has for its object a particularly simple and efficient means for raising and lowering the earth-turning elements thereof; and it consists in the combinations and constructions hereinafter set forth and claimed.

15 In describing this invention reference is had to the accompanying drawing in which like characters designate corresponding parts in all the views.

Figures 1 and 2 are side elevations of a 20 plow embodying my invention, parts of the plow being omitted, and the earth-turning element and coöperating parts being shown in their positions occupied, respectively, when said element is lowered and raised.

25 Fig. 3 is a plan of parts seen in Fig. 1, parts being omitted.

The frame of the plow may be of any desirable form size and construction, and is here shown as comprising opposite longitudinal frame bars 1 having cross bars 2 at their ends.

30 3 is a rear furrow wheel mounted on an axle 4 carried at the lower end of an upwardly-extending spindle 5 which is journaled in the upright bearing 6 formed in a bracket 7 secured to the rear cross bar 2 of the frame.

35 8 is the earth-turning element or plow proper which is carried by the usual beam 9.

40 10 and 11 are front and rear crank members by means of which the earth-turning element is supported and guided when being raised and lowered the front member 10 being shorter than the rear member 11. These 45 crank members 10 and 11 are usually in the form of bails, the ends of which are extended laterally forming spindles 12 which are journaled in bearings provided on the frame. The intermediate portions 13 of the 50 bails are journaled in bearings provided on the beam of the earth-turning element.

The front crank member 10 extends downwardly nearly vertically from its axis and its spindles 12 at its upper end are jour-

naled in bearings 14 provided in upwardly- 55 extending brackets 15 located near the front ends of the frame members 1, and the lower end or portion 13 of the front crank member 10, is journaled or pivoted in a bearing 16 provided on the beam 9. The lower end 60 of the crank member 10 moves upwardly and rearwardly in an arc of approximately a quarter of a circle as indicated by the dotted line 17 during the raising of the earth-turning element and the crank member 65 10 thus moves from a nearly vertical position to a nearly horizontal position.

The pivots or spindles 12 of the rear crank member 11 are journaled in bearings 18 provided at the ends of brackets 19 depending from the rear ends of the frame members 1, and said member 11 extends forwardly and upwardly out of and above the horizontal plane passing through the axis of its lower end, and the portion 13 at its 75 front end is journaled in a bearing 20 provided at the upper end of a bracket 21 associated with the beam 9 of the earth-turning element. During the raising of the plow, the front end of the member 11 moves upwardly and rearwardly in an arc considerably less than a quarter of a circle as indicated by the dotted line 22. Thus the ends of the crank members 10 and 11 are movable in arcs extending between the axes of 80 said members, and the axis of the front crank member 10 is arranged above the horizontal plane of the axis of the rear member 11. By constructing and arranging the members 10 and 11 as described, the end of 85 the front member or bail 10 connected to the beam 9 moves rearwardly during the initial movement of said bail, and the end of the rear member or bail 11 connected to said beam moves upwardly during its initial 90 movement, and consequently the rear end of the beam 9 is first raised faster than the front end of said beam, and the front end of the beam is first lowered to the ground in advance of its rear end. 100

As seen in Fig. 3, the crank members or bails 10 and 11 are arranged out of longitudinal alinement so that the beam 9 is arranged at an oblique angle to the frame or line of travel of the plow. 105

The movement of the earth-turning element is controlled by a lever 23 mounted on a rock shaft 24 journaled in a bearing 25

which is carried at the upper end of an upright bracket 26 supported by a frame bar 1 between the brackets 15 and 19, said shaft 24 having a rock arm 27 extended forwardly and downwardly therefrom, and pivoted at 5 28 to one end of a link 29, which is pivoted at its other end at 30, to the beam 9, the parts 27 and 29 forming a toggle. One of the parts, as the arm 27, is here shown as 10 provided with means for limiting the movement of said parts 27 and 29 and as here shown, the rock arm 27 is provided with a bracket 31 extending beyond the pivot 28, and carrying an adjustable shoulder as a 15 screw 32 extending through the bracket and engaging an edge of the link 29. Obviously, by turning the screw, the extent of movement of the pivot 28, beyond a straight line passing through the axes 24 and 30, can be adjusted. By depressing the lever 23, the beam 9 and the earth-turning element 8 will be raised, and will be guided in their upward movement by the crank members 10 and 11.

20 The earth-turning element is held in its raised position by means of a catch or lock 33 pivoted intermediate of its ends at 34 to the rock arm 27, and provided with a hook-shaped engaging part 35 at the end of one 25 arm, this part 35 moving into and out of engagement with a fixed shoulder 36 provided on the bearing 25. As the lever 23 is depressed and the arm 27 raised, the catch 33 is raised therewith until its end 35 30 latches over the fixed shoulder 36. Said catch is usually formed with a slot 37 which receives the pivot 28 of the toggle. The catch may be moved out of operative position by depressing the other arm 38 thereof and thus moving the hook 35 out of engagement with the shoulder 36, and permitting the earth-turning element 8 to be 35 moved by its own weight to the ground.

30 The raising of the earth-turning element 40 45 8 is facilitated by a horizontally-extending spring 39 connected at its rear end at 40 to a bracket 41 provided on one of the frame bars 1, and at its front end to a link 42, which is pivoted at its front end to a rock arm 43 provided on and rigid with the pivot 12 of the front crank member 10, said

50 arm 43 being arranged at an angle to the front member 10 in order that the leverage of the arm 43 will increase as the plow 8 is raised and the spring 39 grows weaker, and 55 the member 10 moves upwardly. In raising the earth-turning element 8, the depression of the lever 23 sufficiently to move the pivot 28 of the toggle to the front side of the straight line passing through the axes 60 24, 30, moves the arm 43 into a position in which the spring can act most efficiently upon the crank member 10.

What I claim is:—

In a wheeled plow, a frame, an earth 65 turning element having a beam, means for raising and lowering the earth turning element comprising front and rear bails, the front bail extending downwardly and being pivoted at its upper end to the frame, and at 70 its lower end to the beam, the rear bail extending upwardly and forwardly and being pivoted at its rear end to the frame and at its front end to the beam, the front bail being shorter than the rear bail and moving 75 during the raising of the beam from a nearly vertical depending position to a nearly horizontal position through approximately a quarter of a circle, and the longer or rear bail being inclined out of and above the 80 horizontal plane passing through its axis and moving through an arc considerably less than a quarter of a circle, whereby during the movements of the bails, the pivotal connections thereof with the beam move in 85 different directions, that of the front bail moving rearwardly during the initial movement thereof and that of the rear bail moving upwardly so that the rear end of the beam is first raised faster than the front end 90 and the front end is first lowered to the ground in advance of the rear end, substantially as and for the purpose described.

In testimony whereof, I have hereunto signed my name in the presence of two attesting witnesses, at Syracuse, in the county of Onondaga, in the State of New York, this 22nd day of Sept., 1910.

WILLIAM H. LEE.
